UNITED STATES PATENT OFFICE

SAMUEL BRAND, OF DAYTON, OHIO, ASSIGNOR TO THE NATIONAL CASH REGISTER COMPANY, OF DAYTON, OHIO, A CORPORATION OF MARYLAND

CASH REGISTER

Application filed June 13, 1927. Serial No. 198,499.

This invention relates to cash registers and the like machines, and more particularly to improvements in the control of money receptacles therefor.

The principal object of this invention is to provide mechanism for preventing the release of the cash drawer on certain total taking operations of the machine.

With this and incidental objects in view, the invention consists of certain novel features of construction and combinations of parts, the essential elements of which are set forth in appended claims and a preferred form or embodiment of which is hereinafter described with reference to the drawings which accompany and form part of this specification.

Of said drawings:

Fig. 1 is a detail sectional view of a portion of the transaction key bank, its associated differential mechanism and a portion of the drawer opening and selecting mechanism.

Fig. 2 is a detail view of the connection between the drawer selecting and releasing shaft, and the driving shaft therefor.

Fig. 3 is a detail view of the drawer latch releasing mechanism.

Fig. 4 is a detail top plan view of the drawer control mechanism.

Fig. 5 is a side elevation of the total control lever and drawer release control mechanism.

Fig. 6 shows the lever-way for the total control lever.

Fig. 7 is a detail view of the drawer release operating mechanism.

Fig. 8 is a detail view of the drawer control rod.

General description

This invention is adapted to be applied to a machine of the general type illustrated and described in Letters Patent of the United States No. 1,242,170, issued to F. L. Fuller on October 9, 1922, and No. 1,619,796 issued to B. M. Shipley on March 1, 1927. Reference should be made to these patents for a full and complete understanding of the machine.

Machines of this type are usually provided

with a plurality of banks of amount keys and a plurality of banks of transaction or control keys. One of the banks of control keys is usually designated as the bank of clerks' keys. These keys are used to select the totalizers on which are accumulated various amounts entered in the register by the individual clerks. The clerks' keys also control the section of the cash drawer, of which a plurality, one for each of the nine clerks' keys, is provided.

Generally, heretofore, the selected cash drawer was rendered accessible on each operation of the machine. However, it is desired to retain the cash drawer in its inaccessible position on certain total taking operations. Mechanism, comprising the present invention, is therefore provided which, under control of the well known total control lever, renders the drawer releasing mechanism ineffective on certain operations of the machine. It will be evident from the drawings accompanying and forming a part of this application, and from the following description, that this mechanism can be constructed to render the drawer release mechanism ineffective on any one or a plurality of different operations under the control of the total control lever, and it is not intended to limit the invention to the particular form of embodiment shown herein, nor is it confined to the particular type of register to which the invention is herein shown applied.

Keyboard mechanism

The keyboard of the machine to which the present invention is shown applied, is substantially the same as that shown in the above referred to patent to Shipley, and only such parts thereof as concern the present invention, are shown herein.

Only a brief description of the clerks' keys will be given, as this mechanism is old and well known in the art.

The clerks' keys 30 (Fig. 1) are mounted in a frame 31, supported in the machine by two rods, only one of which, 32, is shown. Nine clerks' keys are provided in this bank, but as the upper part of the bank is broken away, only four are shown.

The keys 30, when depressed, are so held by a spring pulled detent 33, having a hook 34 formed thereon opposite each of the keys 30, which, after a key is depressed, engages a 5 pin 35 on the key thereby holding the key in its depressed position. When released near the end of the operation, by mechanism well known in this type of machine, the depressed key is returned to its normal, outward position 10 by a spring not shown. The detent 33 is swung at its lower end on an arm 36 and at its upper end it is supported by a similar arm not shown herein. A releasing bar 37 is shown in Fig. 1, but as it is old and well known in the art and is not pertinent to the 15 present invention, no description thereof will be included herein.

Differential mechanism

20 The differential mechanism associated with the keys 30 is well known in the art and only a brief description thereof will be included in this application.

The differentially movable arm 40 (Fig. 25 1), pivoted on a stud 41, is connected to a driving segment 42, also pivoted on the stud 41, by a latch 43 mounted on the arm 40, a bell crank 45, and a link 44. The latch 43 is held in the position shown by a spring. The 30 segment 42 is given a regular excursion first clockwise and then back to its normal position by a pair of cams 46 pinned to a shaft 53, which is the well known main drive shaft common in machines of this type. Cooperating 35 with the cams 46 are two antifriction rollers 47, carried on a Y-shaped lever 48, which at its upper end is connected to the segment 42 by a link 49. The cams 46 receive one clockwise rotation on each operation of the 40 machine, which, through the lever 48 and the link 49, gives the segment 42 its regular excursion. On its upward movement the segment 42 carries the arm 40 with it until the 45 latch 43 strikes a depressed key and is disconnected from the driving segment 42, in a manner old and well known in the art. When this occurs, the differentially movable arm 40 is stopped in a position corresponding to the key depressed. If no key is depressed in 50 this bank, the latch is disconnected by a zero stop pawl 50, the operation of which is very well known, and fully illustrated and described in the patent to Fuller numbered 1,242,170, issued October 9, 1922. The bell 55 crank 45 is connected by a pin and slot connection to a reset spider 51, shown broken away, which is pivoted on the stud 41 and lies in the same plane as the zero stop pawl.

When the segment 42 is rocked counter-clockwise to its normal position, a surface thereon will contact a pin 52 on the arm 40 and return this arm to its normal position.

Drawer selection

55 As previously mentioned, the machine is

provided with a plurality of cash drawers, the topmost one 55 (Fig. 1) of which is illustrated herein, the other drawers being exact duplicates. These drawers are of the usual design provided in machines of this type, and a complete description thereof is not thought necessary to an understanding of the present invention.

70 Each of the drawers 55 (Fig. 1) is slidably mounted in an opening in the base of the machine. A bracket 56 secured on the back of each drawer, has pivoted thereto a latch 57, spring held in its latched position. A shoulder 58 of the latch contacts a plate 59 secured to a bar 60 extending across the rear of the machine. When the drawer is unlatched, as will presently be described, it is propelled forwardly out of the drawer cabinet and into its accessible position by the sudden expansion of two springs 61, only one of which is shown.

75 The cash drawer to be released is selected by a vertical shaft 65 (Fig. 1) under control of the keys 30. Spirally located around the shaft 65 is a plurality of fingers 66, one opposite each of the nine drawers. Only the upper two of the key fingers are shown herein.

80 The shaft 65 (Fig. 1) is positioned by the differential mechanism described above and in the following manner. Pivoted on the differentially movable arm 40 is a beam 67 which is bifurcated at its right hand end and straddles a pin 68 mounted in a link 69. At 85 its lower end this link 69 is pivotally connected to an arm 70, free on a shaft 71, supported in the right side frame 87 (Fig. 4) and the left side frame, not shown, of the machine. A roller 86 (Fig. 1) carried by the Y-shaped lever 48, is adapted to cooperate with the lower part of the beam 67 and position this beam and the link 69 differentially, as determined by the key depressed.

90 The arm 70 has secured thereto a segment gear 72, meshing with teeth formed on one end of a horizontally disposed rack 73. The forward end of this rack is slidably supported in a cross bar 74, supported by the machine base 76. At its right hand end, as viewed in Fig. 1, the rack 73 is guided in a slot cut in a projection 75 on the base of the machine. At 95 its right hand end the rack 73 is provided with teeth meshing with a gear 77 pinned to a short shaft 78 mounted in two brackets 79 and 80 (Fig. 4) secured to the base 76 of the machine. At its left hand end, as viewed in Fig. 4, the shaft 78 has pinned thereto a spiral gear 81 (see also Fig. 1) which meshes with a spiral pinion 82, fast on a short vertical shaft 83. At its lower end the shaft 83 has a tenon 84 (Fig. 2) formed thereon to slide in a mortise cut in the enlarged upper 100 end of the shaft 65.

105 It can be seen from Figs. 1 and 2 that, due to the constructions of these parts, rotary 110

movement of the spiral pinion 82 will be transmitted to the shaft 65, and that a vertical movement of the shaft 65 can be effected without raising the spiral pinion 82 and the shaft 83.

When one of the keys 30 has been depressed and the machine operated, the clockwise movement of the differentially movable arm 40, by means of the beam 67, will move the link 69 down and rock the arm 70 and segment 72 clockwise. This movement of the segment will slide the rack 73 toward the left and rotate the gear 77, shaft 78 and spiral gear 81 in a clockwise direction. The movement of the gear 81 is transmitted by the spiral pinion 82 and short shaft 83 to the shaft 65 to position this shaft as determined by the key depressed.

As mentioned above, the shaft 65 has a plurality of fingers 66 spirally disposed around it. Thus if the lower key is depressed, the shaft 65 will be rotated through the differential mechanism to move the finger 66 for the first or topmost drawer, into co-operative relation with that drawer.

Pivoted on a stud in the cross bar 60 (Figs. 1 and 3) is a lever 90, the movement of which is limited by a pin 91, mounted in the cross bar 60 and projecting through an opening in the lever. The lever extends laterally in the machine and normally lies just above the latch arm 57 for the cash drawer. When the shaft 65 is raised, in a manner presently to be described, the right hand end of the lever 90 will contact and move the latch 57 downwardly to disengage the shoulder 58 (Fig. 1) from the plate 59 and thereby permit the springs 61 to propel the drawer forwardly to its accessible position. The means for rocking the lever 90 will now be described.

From Figs. 1 and 2 it can be seen that a shell 85, is secured to the enlarged upper end of the shaft 65 and has cut therein an annular groove 92. A shaft 93 loosely mounted in two similar brackets 94 (Fig. 4) secured to the base of the machine, has pinned to its right hand end a U-shaped member 95 carrying two pins 96 projecting into the annular groove 92 in the shell 85. Pinned to the shaft 93 near its left hand end is an arm 97 having integral therewith a finger 98 held in contact with the end of one arm 99 of a bell crank 100 by a spring 101, one end of which is attached to an upwardly extending lobe 102 on the arm 97. The bell crank 100 is pivoted on a short shaft 103 (Figs. 4, 5 and 7) mounted in a bracket 104, secured to the base of the machine. An arm 105 (Fig. 7), also free on the shaft 103 has a finger 106 adapted to cooperate with a rod 107 slidably mounted in a bearing 108 integral with the bell crank 100. At its left hand end, as viewed in Fig. 7, the arm 105 carries a roller 109 adapted to cooperate with a cam 110 pinned to a shaft 111. The roller 109 is held in contact with

the cam 110 by a spring stretched between the arm 105 and the arm supporting the bearing 108. The shaft 111 is the well known printer drive shaft in machines of the type to which this invention is shown applied, and is fully illustrated and described in the above mentioned patents. The cam 110 is shaped to give the arm 105 a rocking movement first counter-clockwise and then clockwise to its normal position near the end of each operation of the machine. The counter-clockwise movement of the arm 105 will, through the finger 106 thereof, engaging the rod 107, rock the bell crank 100 and the arm 99 counter-clockwise. As the arm 99 is rocked counter-clockwise it will rock the arm 98, shaft 93 and the U-shaped arm 95 counter-clockwise, as viewed in Fig. 1, thereby raising the shaft 65 to release the cash drawer. The cam 110 will then permit the parts to return to their normal positions, as shown in Figs. 1, 4 and 7. When the shaft 65 is moved upwardly, the finger 66, which has been positioned previously, under control of the keys 30, as described above, will cooperate with the left hand end of the lever 90 and rock this lever clockwise, thereby moving the latch 57 down, and releasing the cash drawer selected.

The shaft 111 is mounted in a bracket 112, supported by the base of the machine, and at its forward end is journaled in a printer frame, not shown. Pinned on the shaft 111 is a spiral gear 113, meshing with a spiral gear 114 (Fig. 7), pinned to the main drive shaft 53 of the machine. The movement of the shaft 53 and the gear 114 imparts one counter-clockwise rotation to the gear 113 and shaft 111 (Fig. 7) on each operation of the machine.

Drawer release disabling mechanism

As previously stated, it is desired to retain the cash drawer in its inaccessible position on certain operations of the machine. Mechanism under control of the well known total control lever for disabling the drawer release mechanism, will now be described.

Referring to Figs. 5 and 7, it will be remembered that the bell crank 100 is rocked counter-clockwise to release the selected drawer by the finger 106 on the arm 105 contacting the surface of the rod 107, which is slidably in the bearing 108 of the bell crank 100. It can be seen from Figs. 7 and 8 that with the rod 107 positioned with one of the notches 126 or 127 opposite the projection 106, the rod 107, and consequently the arm 99 will not be moved when the arm 105 is rocked counter-clockwise by the cam 110. The finger 106 will move idly into the notch, thus preventing the shaft 65 from being raised and the drawer released. The rod 107 is positioned by the total control lever 115 in the following manner:

The lever 115 (Fig. 5) is the usual total

control lever with which machines of this type are provided, and is for the purpose of controlling the machine for total and subtotal taking operations. The lever 115 is secured to a disk 116, pivoted on a stud 117 projecting from the right side frame 87 (Fig. 4) of the machine. The disk 116 is connected by a link 118 to an arm 119 loosely pivoted on the shaft 71. A pin 120 mounted in a downwardly extending portion of the arm 119 projects through the bifurcated end of an arm 121, pinned to a shaft 122. This shaft 122 (Figs. 4 and 5) is loosely mounted in a lug 123 cast on the base 76 of the machine. Pinned to the left hand end of the shaft 122 (Fig. 4) is an arm 124, connected by means of a link 125 to the rod 107 previously described.

The counter clockwise movement of the lever 115 (Fig. 5) from its add position to any of its reset positions will, through the link 118, rock the arm 119 counter-clockwise which, by means of the pin 120, will rock the arm 121, shaft 122 and arm 124 clockwise. This movement of the arm 124 will move the link 125 and the rod 107 to the right, as viewed in Fig. 5. Likewise the clockwise movement of the lever 115 will, through the parts just described, slide the rod 107 to the left to a position corresponding to that to which the lever 115 is adjusted.

Referring to Figs. 6 and 8 it can be seen that the rod 107 is provided with positions corresponding to the positions to which the total control lever 115 is capable of being adjusted. As shown in Fig. 8 the rod 107 has no notch opposite the add, first read and first reset positions. Thus, if the total control lever 115 is moved to any one of these positions and the machine operated, the cash drawer will be released and rendered accessible. However, if the lever 115 is adjusted to either the second or third position above or below the add position, the drawer will not be released, as it will be noted from Fig. 8 that the notches 126 and 127 are opposite those positions and therefore the drawer cannot be released.

Obviously the drawer release mechanism can be disabled with the lever 115 in any of its positions or any number of positions by merely cutting a notch in corresponding position on the rod 107 in which it is desired to have drawer release mechanism remain ineffective.

While the forms of mechanisms herein shown and described are admirably adapted to fulfill the objects primarily stated, it is to be understood that it is not intended to confine the invention to the forms or embodiment herein disclosed, for it is susceptible of embodiment in various forms all coming within the scope of the claims which follow.

What is claimed is:

1. In a cash register, the combination of a

plurality of keys, a differential mechanism controlled thereby, a plurality of receptacles, a finger shaft controlled by said differential mechanism, the position of which shaft determines which of said receptacles will be released, a cam and arm for raising said finger shaft to release said selected receptacle, a manually operable lever, and a rod shiftable longitudinally by said lever and having notches, the positions of which render said releasing means ineffective upon operation of the machine.

2. In a drawer releasing mechanism, the combination of an arm for actuating the releasing mechanism, a cam for actuating said arm, a second arm actuated by said first arm, and a notched rod slidably carried by said second arm and adapted to be manually positioned to form an operative connection in a plurality of positions between said first and said second arms.

3. In a drawer releasing mechanism, the combination of an arm for actuating the releasing mechanism, a cam for actuating said arm, a second arm adapted to be actuated by said first arm, and a manually adjustable rod carried by said second arm and having high portions and notches adapted to form an operative connection in a plurality of positions between said first arm and said second arm when a high portion is opposite said first arm, and to render said releasing means ineffective when a notch is opposite said first arm.

4. In a machine of the class described, the combination of a bank of keys, a plurality of drawers, means differentially adjustable under control of said keys for selecting the drawer to be released, means for releasing the drawer selected, a total lever having an add position and a plurality of total controlling positions, and means operated by said lever for rendering said releasing means ineffective for a predetermined number of positions of said lever.

5. In a drawer releasing mechanism, the combination of an arm for actuating the releasing mechanism; a cam for actuating said arm; means actuated by said arm; a manually operable lever; and a rod shiftable differentially and longitudinally by said lever, to form an operative connection between said arm and said means when the rod is shifted into certain positions, and to prevent an operative connection from being formed when the rod is shifted into other positions.

In testimony whereof I affix my signature.
SAMUEL BRAND.
